(57) CLAIM

The ornamental design for an outdoor furniture surface protector, as shown and described.

DESCRIPTION

FIG. 1 is a top perspective view of an outdoor furniture surface protector in a first embodiment of my new design;

FIG. 2 is a bottom perspective view thereof;

FIG. 3 is a front side view thereof;

FIG. 4 is a rear side view thereof;

FIG. 5 is a right side view thereof;

FIG. 6 is a left side view thereof;

FIG. 7 is a top view thereof;

FIG. 8 is a bottom view thereof;

FIG. 9 is an environmental perspective view thereof;

FIG. 10 is an environmental bottom perspective view thereof;

FIG. 11 is a top perspective view of an outdoor furniture surface protector in a second embodiment of my new design;

FIG. 12 is a bottom perspective view thereof;

FIG. 13 is a front view thereof;

FIG. 14 is a rear view thereof;

FIG. 15 is a right side view thereof;

FIG. 16 is a left side view thereof;

FIG. 17 is a top view thereof;

FIG. 18 is a bottom view thereof;

FIG. 19 is an environmental perspective view thereof; and,

FIG. 20 is an environmental bottom perspective view thereof.

Where included, broken lines showing environment or structure are for illustrative purposes only and form no part of the claimed design.

1 Claim, 18 Drawing Sheets
